UNITED STATES PATENT OFFICE

HUGO VOGL, OF PRAGUE, CZECHOSLOVAKIA

SCREW VISE

Application filed January 29, 1931, Serial No. 512,118, and in Czechoslovakia September 12, 1930.

The object of the present invention is a screw-vise consisting of a lower slide extended at its front end upwardly to form a stationary jaw and fitted with a threaded spindle, and of a second jaw moved to and from the stationary jaw parallelly with the slide in the direction of the axis of the threaded spindle. The substance of the invention resides in this that both the lower slide and its upwardly extending stationary jaw formed of one piece consist of a set of adjacent and interconnected relatively thin metal laminæ or sections having a mutually coincident longitudinal profile of the whole piece, i. e., of the slide together with the jaw. The other slidable jaw together with its guiding portion is of usual construction.

In previous screw-vises the slide-body of which together with the stationary jaw are made of cast-iron (such screw-vises are liable to burst in the place where the slide is bent to form the upwardly extending leg with the jaw) or if they are forged from a single piece of metal are very difficult and costly to make. The new arrangement shows following substantial advantages:

The manufacture of screw-vises from pressed out metal-sections is very cheap and simple, since it facilitates punching of sections of any desired profiles from sheet-metal for most various purposes of screw-vises, by aid of suitable punching devices. A screw-vise produced in this manner may be of sheet metal of any desired strength, so that screw-vises can be made even from the hardest sheet-steel, which do not burst in the dangerous bend and at the same time they can easily be produced simply by connecting these sections together instead of the previous forging or cutting out of the body of the screw-vise from a single piece of hard material, such as steel and the like. Moreover a laminated screw-vise possesses the advantage, especially for fine work, that an article treated therein is not subject to vibrations, which in the previous screw-vises is caused by the whole mass of screw-vise being set into vibration during filing. A laminated body does not vibrate, since the slight vibrations of laminæ are mutually compensated.

The drawing shows by way of example the construction of the screw-vise according to the invention. Fig. 1 is an axial longitudinal section of the whole screw-vise in line I—I Fig. 2 passing directly between two sections; 55 Fig. 2 is a cross-section of the screw-vise in line II—II Fig. 1. Fig. 3 is the section of a detail from Fig. 1 in line III—III.

With the screw-vise according to the invention the lower slide, as well as its stationary jaw 2 extending at its front end upwardly, are formed of a set of relatively thin sections 3 disposed one by one in a successive row and connected together by rivets and bolts, said sections being in smaller hand-vises 60 3 mm thick and punched out in the desired profile from sheet-metal, preferably of sheet-steel. The upper slidable jaw 4 with guiding portion 4' is solid as usual and therefore in Fig. 1 it appears in section, while the lower slide 1 together with the jaw 2 does not appear in section, since the sectional plane passes directly between two adjacent sections. The jaw 2 is provided as usual with a bore 5 to receive the threaded spindle 6 and with a guiding sleeve 7. This guiding sleeve 7 is rigidly mounted within the jaw 2 and its bore is dimensioned so that the screw-vise spindle is free to rotate therein. The purpose of the guiding sleeve is only to protect the said spindle from being damaged. The threaded spindle 6 is guided by a threaded bore in the upper slide 4' of the movable jaw 4. The steel-plates 8, 8 are fastened by screws 75 80 85 as usual.

The sections 3 in the jaw 2 are connected together by rivets 9 having countersunk heads 9'; the rivet-heads of the lower slide may project (Fig. 3). Produced sheet-metal assembly 90 is finally clamped together between two lateral pressure plates 3'.

The rear rivet-bolts 9 (Fig. 1) serve at the same time for the attachment of two end-plates 10, the shoes 11 of which together with the sheet-metal assembly 3 form a dovetail-groove for the upper slide 4' of the jaw 4 and are provided with lugs 12 by aid of which the screw-vise is attached to a shop-bench or the like. 95 100

What I claim is:

1. In a screw-vise consisting of a lower slide with a stationary jaw and a threaded spindle and of a slidable jaw with upper guiding portion, the stationary jaw integral with the lower slide formed of a set of adjacent thin metal-sections connected together by rivet-bolts, said sections having a mutually coincident longitudinal profile of the whole piece, guiding and fastening end-plates having shoes and lugs serving at the same time for clamping the sections together by aid of common rivet-bolts.
2. In a screw-vise consisting of a lower slide with a stationary jaw and a threaded spindle and of a slidable jaw with upper guiding portion, the stationary jaw integral with the lower slide formed of a set of adjacent thin metal-sections connected together by rivet-bolts, said sections having a mutually coincident longitudinal profile of the whole piece, guiding and fastening end-plates having shoes and lugs serving at the same time for clamping the sections together by aid of common rivet-bolts, a guiding sleeve fixed within the stationary jaw to protect the screw-vise spindle from being injured, said spindle being guided by a threaded bore provided in the upper slide of the slidable jaw.
- 30 In testimony whereof I have signed my name to this specification.

HUGO VOGL.
